OILING DEVICE

Roy O. Allen, Athens, Pa., assignor to Ingersoll-Rand Company, Jersey City, N. J., a corporation of New Jersey

Application January 31, 1939, Serial No. 253,801

1 Claim. (Cl. 184—55)

This invention relates to fluid actuated tools, and more particularly to an oiling device for fluid actuated tools of the hammer type, as for example rock drills.

5 One object of the invention is to simplify the matter of supplying oil to the movable parts of the tool.

Another object is to introduce the oil into the pressure fluid stream at a point closely adjacent 10 the fluid actuated elements of the tool.

Other objects will be in part obvious and in part pointed out hereinafter.

In the drawing accompanying this specification and in which similar reference numerals 15 refer to similar parts,

Figure 1 is an elevation, partly in section, of a fluid actuated tool of the hammer type equipped with an oiling device constructed in accordance with the practice of the invention, and

20 Figure 2 is a similar view taken through Figure 1 on the line 2—2.

Referring more particularly to the drawing, 20 designates, in general, a fluid actuated percussive tool, as for example a tie-tamper, and 21 the tool casing to the rear end of which is connected a hollow rod 22 which may serve as a handle and also as a conduit for conveying pressure fluid to the tool.

The casing 21 is bored to provide a piston 20 chamber 23 for the accommodation of a hammer piston 24 reciprocable in the piston chamber 23 to actuate a working implement (not shown). Adjacent the rearward end of the piston chamber 23 is a valve mechanism to effect the distribution 35 of pressure fluid to the piston chamber 23 for actuating the piston.

The valve mechanism shown comprises a pair of plates 25 and 26 of which the latter is recessed to provide a valve chamber 27 for a distributing valve 28. The distributing valve is of the well known oscillatory plate type of which the wings control inlet passages 29 and 30 leading to the rear and front end, respectively, of the piston chamber 23.

45 The pressure fluid distributed by the valve 28 is conveyed to the valve chamber by a passage 31, in the casing 21, opening into a supply chamber 32 rearwardly of the valve mechanism, and passages 33 in the plate 26 afford communication 50 between the supply chamber 32 and the valve chamber 27.

The oiling device, constructed in accordance with the practice of the invention, is located in the rearward end of the casing 21 between the rod 22 and the valve mechanism. It comprises

an oil reservoir 34 which encircles, in the present instance, the portion of the casing defining the passage 31. At the upper end of the oil reservoir 34 is an opening 35 for the introduction of oil into the reservoir and said opening is normally closed by a plug 36.

5 In the front end of the reservoir 34 is a rib 37 having a bore 38 which cooperates with the reservoir through a port 39 in the rib. The bore 38 extends entirely through the casing and comprises an enlarged portion 40 that is normally closed by a plug 41 and a reduced portion 42 into which the port 39 opens. A port 19 in the casing affords communication between the enlarged portion 40 and the supply chamber 32.

10 The reduced portion 42 of the bore 38 serves as a guide for a plunger 43 which is reduced in the longitudinal plane of the port 39 to provide a stem 44 that extends into the enlarged portion 40 of the bore. The stem 44 carries a valve 45 20 which seats against a seating surface 46 at the end of the reduced portion 42 of the bore to control communication between the portions 42 and 40.

15 The valve 45 may consist of rubber and is 25 clamped between rigid washers 47 and 48 by a nut 49 threaded on the stem. A spring 50 interposed between the plug 41 and the nut 49 normally maintains the valve 45 seated against the seating surface 46.

30 The plunger 43 is of such length that when the valve 45 is in closed position the outer end of the plunger will be flush with or protrude only slightly from the casing 21. A depression 51 is 35 preferably formed in the casing around the outer end of the plunger to permit the entrance of the finger actuating the plunger.

In the operation of the device and with the pneumatic tool 20 in its normal operating position oil will flow from the reservoir through the port 39 into the portion of the bore 38 encircling the stem 44. Whenever it is considered advisable to introduce oil to the distributing and percussive elements of the tool the plunger 43 is actuated toward the plug 41 by pressure applied 45 against the exposed end of the plunger.

40 This is preferably done while the tool is idle and immediately before an operating period. The oil encircling the stem 44 will then be transferred into the enlarged portion 40 of the bore 50 whence the oil flows through the port 19 into the supply chamber 32. The plunger 43 is then released and will be immediately returned to a position in which the valve 45 again closes the reduced portion 42 of the bore.

The oil thus introduced into the supply chamber will flow through the passages 33 into the valve chamber and when the tool is again set in operation the pressure fluid flowing through the valve chamber will convey the oil to all the different surfaces to which the pressure fluid has access including, of course, the piston chamber 23.

I claim:

10 In an oiling device for fluid actuated tools, the combination of a casing and fluid actuated means in the casing, a channel in the casing for conveying pressure fluid to the fluid actuated means,

a reservoir in the casing for oil and having a port, a chamber in the casing between the channel and the reservoir having an enlarged portion and a reduced portion, the reduced portion communicating with the port, a port to afford communication between the enlarged portion and the channel, a spring-opposed manually operable plunger in the chamber for periodically supplying oil from the reduced portion to the enlarged portion, and a valve on the plunger to control communication between the said portions of the chamber. 5 10

ROY O. ALLEN.
